UNITED STATES PATENT OFFICE.

GEORGE W. FOLICK, OF BUFFALO, NEW YORK.

COMBINATION-LOCK.

1,375,044.

Specification of Letters Patent. Patented Apr. 19, 1921.

Application filed September 9, 1920. Serial No. 409,077.

To all whom it may concern:

Be it known that I, GEORGE W. FOLICK, a citizen of the United States, residing at Buffalo, in the county of Erie and State of New York, have invented new and useful Improvements in Combination-Locks, of which the following is a specification.

This invention relates to a combination lock especially desirable for locking various parts of automobiles, such as the hood-doors, and a shut-off valve controlling the fuel feed to the carburetor, with a view to preventing theft of the car, but the lock is also applicable to safe-doors as well as other parts.

The object of the invention is the provision of a strong and practically burglar-proof lock of this character which is at the same time light, compact and inexpensive to manufacture.

In the accompanying drawings: Figure 1 is a horizontal section of the front portion of an automobile equipped with the lock. Fig. 2 is an enlarged face view of the lock and a fragment of the instrument-board. Fig. 3 is a transverse section of the lock on line 3—3, Fig. 2. Fig. 4 is a view of the inner end of one of the tumbler shafts, and the tumbler mounted thereon. Fig. 5 is a fragmentary sectional elevation thereof. Fig. 6 is a sectional side elevation of the main shaft or spindle. Fig. 7 is a cross section thereof on line 7—7, Fig. 6, associated with one of the notched tumbler-disks, which is shown in dotted lines. Fig. 8 is a view similar to Fig. 7, showing a different position of the tumbler-disk, which latter is shown in dotted lines.

Similar characters of reference indicate corresponding parts throughout the several views.

The stationary frame of the lock comprises a solid head or body 10 projecting from the face of the instrument-board 11 and a casing 12 secured by screws 12^a or other means to the back of said body. The latter preferably has a conical portion 13 seated in a corresponding opening of the instrument-board in which it is secured by screws 14.

Journalized axially in the body 10 and the casing 12 is the main operating shaft or spindle 15 of the lock. As shown in Fig. 3, this shaft is held against longitudinal displacement in one direction by a shoulder 16 abutting against a corresponding one in the

bore of the body 10, and in the opposite direction by a shaft-shoulder 17 abutting against the front wall of the casing 12. At its front end the shaft has a knurled knob 18 for turning it, this knob being removably secured in place by a pin 19 or other appropriate means. At its opposite end said operating shaft carries a crank, rock-arm or other suitable element 20 for transmitting its oscillating or rotary motion to the part or parts to be locked. For example, in the drawings the arm 20 is connected by a link 21, bell crank 22 and link 23, with the actuating arm 24 of a cut-off valve 25 located in the fuel feed pipe 26 leading to the carburetor 27, so that upon turning the shaft in one or the other direction, said valve is opened or closed. To this shaft may also be coupled the locking bolts 28 or 29 equivalent fastening devices of the hood-doors 29, so that oscillation of said shaft causes the bolts to be either projected or retracted to lock or unlock the doors. In the particular construction shown in the drawings, each bolt passes through a pair of lugs 30 carried by the hood-body and an intermediate lug 31 carried by the corresponding door and the bolt is connected with the operating shaft 15 by a bell crank 32, link 33 and a universal joint 34, the rigid stem 35 of the inner joint-member being secured obliquely in an opening of said shaft, as shown in Fig. 1.

The operating shaft is locked against rotation in either direction by a plurality of rotary disks, washers or circular tumblers 36 arranged obliquely to the axis thereof and adapted to interlock with correspondingly-arranged segmental recesses 37 in the periphery of the shaft. As shown in Fig. 3, each of these tumblers is mounted transversely on the inner end of a rotary shaft 38 journaled in the lock-body 10 and inclined to the axis of the main shaft 15, the several tumbler-shafts converging toward said shaft. The tumblers are rigidly mounted upon their shafts and each is provided in its edge with a segmental notch 39 curved and beveled to conform to the periphery of the main shaft, so that when the notch is brought in register with the corresponding recess 37 of the shaft by the rotation of the tumbler-shaft, as shown in Fig. 7, the tumbler clears and unlocks the main shaft, leaving it free to be turned in either direction by its knob 18. When, how-

ever, the tumbler is turned to break register between its notch and said recess, as shown in Fig. 8, the solid, unnotched margin of the tumbler interlocks with the recess, as shown in Fig. 8, and blocks rotation of the main shaft in either direction, this locking action being obviously due to the oblique arrangement of the tumbler and said recess relative to the axis of the main shaft.

10 The latter remains locked unless the notches of all the tumblers are brought opposite the corresponding shaft-recesses.

Each tumbler-shaft is provided at its outer end with a knurled operating knob 15 40 removably pinned or otherwise attached thereto. The bases of these knobs are graduated and coöperate with numbered dials 41 on the face of the fixed head 10, in a manner common to combination locks.

20 To permit changes of the combination, the tumblers are capable of rotary adjustment on their shafts. Preferably, this is accomplished by providing each tumbler with a square or other flat-sided bore and 25 correspondingly shaping the reduced inner end of its shaft, as shown, the tumbler being held in place by a screw 42 and washer 43, or other means. Upon removing these screws and washers, the tumblers can be 30 turned one or more quarters on their shafts to change the combination.

It will now be understood that when the chauffeur desires to lock his car, he turns the several tumbler knobs 40 to the pre- 35 determined numbers on the dial 41 to release the operating shaft 15, after which he turns the latter in the proper direction to close the shut-off valve 25 and project the hood-locking bolts 28, and finally rotates the several tumbler-shafts to lock the operating 40 shaft, as hereinbefore described. To unlock the hood and open the shut-off valve, the main shaft is released, as before, and then turned in the reverse direction.

45 The tumblers, being housed within the tight casing 12, are invisible and inaccessible in the assembled condition of the lock, and even if the knobs of the tumbler shafts were broken off in an attempt to unlock the 50 operating shaft, the lock could still not be opened because of the engagement of the tumbler disks with the recesses of the operating shaft.

The lock comprises few parts, enabling it to be manufactured at relatively low cost. 55 It is moreover, light and compact and therefore especially suitable for use on automobiles, although it is equally serviceable for safe-doors, tool-boxes and other articles.

I claim as my invention :

1. A combination lock, comprising a lock-body, an operating shaft journaled therein and having a locking recess arranged obliquely to the axis of the shaft, an inclined rotary tumbler-disk arranged to engage 65 edgewise in said recess to lock said shaft against rotation, said disk having a releasing-notch in its edge, and means for turning said tumbler-disk.

2. A combination lock, comprising a lock-body, an operating shaft journaled therein and having an inclined locking recess, and a tumbler shaft arranged at an angle to said operating shaft and carrying a notched, inclined tumbler-disk arranged to engage 75 edgewise in said locking recess, said tumbler-disk being capable of rotary adjustment on its shaft.

3. A combination lock, comprising a lock-body, an operating shaft journaled therein 80 and having a plurality of inclined locking recesses in different sides thereof, rotary tumbler shafts converging toward said main shaft and each carrying an inclined tumbler-disk arranged to interlock with one of 85 said shaft recesses, each tumbler-disk having a peripheral notch, and means for turning said operating and tumbler shafts.

4. A combination lock, comprising a frame including a solid head and a closed 90 casing applied to the back of the head, an operating shaft journaled in said head and said casing and provided with shoulders abutting against said parts, respectively, the portion of said shaft within said casing 95 having inclined locking recesses on different sides thereof, tumbler-shafts converging toward said operating shaft and each provided within said casing with an inclined tumbler-disk arranged to engage edgewise 100 in one of said recesses and having a segmental notch in its edge, and means for turning said operating and tumbler shafts.

GEORGE W. FOLLICK.
